UNITED STATES PATENT OFFICE

JAMES A. BISHOP, DECEASED, LATE OF MASCOUTAH, ILLINOIS, BY LULU H. BISHOP,
ADMINISTRATRIX, OF MASCOUTAH, ILLINOIS

STATIC ELIMINATOR

Application filed March 29, 1928, Serial No. 265,591. Renewed June 11, 1931.

This invention has to do with improvements in radio reception and the like. It has to do particularly with improvements in means for eliminating interference due to the presence of static. The present invention constitutes in some respects an improvement over the co-pending application for Letters Patent of the United States, Serial No. 115,007, which was filed June 10, 1926, and became Letters Patent No. 1,689,224, issued October 30, 1928. In that application there is disclosed certain apparatus and a system for separating and dissipating the static interference from the radio signals, in which system and apparatus use is made of a system of magnetic shields or shields of magnetic material surrounding or in conjunction with the conductors which carry the radio signals proper. That application also discloses an arrangement for dissipating the static interference so separated from the radio signals proper.

The present invention includes an arrangement whereby the effect of these mechanical shields may be controlled and regulated by the user; for which purpose, according to the present invention there is provided means for subjecting the material of the shields themselves to the supplementing influences of a magneto-motive force the strength of which may be regulated by the user.

This control of the magnetization of the shields also makes it possible to control the polarity of the magnetism of said shields so that it is possible to make the same either positive or negative as desired. This is a very desirable feature as will be more apparent from the following explanation of the principles of operation of these devices.

There is associated with the shield a condenser composed of a multiplicity of plates sufficient to insure nonsaturation from violent electric charges that may come over from the aerial. This condenser is provided with a ground connection to discharge any bolt of static that may be deposited therein. However, by reason of the control of the magnetic condition of the shield there is maintained an equilibrium of electro-magnetic lines of

force between the polar terminals, the aerial connections, and the condenser plates.

In the drawings has been illustrated a construction of device embodying the features of the present invention in which

Figure 1 shows a plan view of an assembled device embodying the features of the present invention and mounted upon a common base board;

Fig. 2 shows a side elevation corresponding to Fig. 1;

Fig. 3 shows a cross section on the line 3—3 of Fig. 1 looking in the direction of the arrows and on enlarged scale, being a section through the condenser;

Fig. 4 shows a cross section on the line 4—4 of Fig. 1 looking in the direction of the arrows on enlarged scale, being a section looking towards the exciting coils; and

Fig. 5 shows a fragmentary longitudinal section on the line 5—5 of Fig. 1 looking in the direction of the arrows and on enlarged scale, showing the manner in which the magnetic lamination plates are individually connected to the various tubular magnetic shields.

In the construction shown in the drawings there is provided a series of magnet cores 7, 8, 9 and 10 respectively. These are all magnetized in such a manner that they are of the same polarity at one side of the structure and of the opposite polarity at the other side. The left hand ends when viewed as in Figs. 1 and 2 are of north polarity and the right hand ends are of south polarity.

The magnets themselves may be either permanent or electro-magnets but preferably the latter since by this means it is possible to control the degree of magnetization very closely. Furthermore, it is possible by the use of electromagnets to operate at a higher degree of magnetization than is practically feasible with permanent magnets.

Accordingly there are illustrated the solenoids 11, 12, 13 and 14 on the respective magnet bars, 7, 8, 9 and 10. These solenoids are all connected up either in series or parallel, preferably in series with the electrical terminals 15 and 16. By this means the magnetiza-

tion of the entire group is simultaneously controlled.

The windings of the solenoids are in such directions as compared to the electrical connections between them, as to magnetize all of the bars north pole at one and south pole at the other end as shown in Figs. 1 and 2.

The incoming radio signal currents are caused to flow in proximity to the north magnetic or positive magnetic poles. Any convenient arrangement may be used for accomplishing this result but preferably one in which the maximum effect and greatest benefit per unit of energy expended will be produced.

With the above object in view it is preferred to provide a series of tubular magnetic shields 17, preferably in two layers as clearly indicated in Figs. 2 and 5, and there preferably being an even number of such shields in each layer. These shields are preferably made of spirals of soft magnetic wire although obviously other constructions may be adopted.

In order to insure a maximum degree of magnetic contact and influence between the cores 7, 8, 9 and 10 and the shields, the cores are preferably made of flat laminations in sufficient number so that the consecutive laminations may be curled around and envelop the respective magnetic shields as indicated in Figs. 2 and 5. For this purpose there are preferably as many laminations in each core as there are magnetic shields, namely, twenty.

The attaching ends of the laminations are also preferably flexed forward slightly adjacent to the points where they wrap around the shields so as to provide a slight amount of springiness or resiliency at these points of support. This is well shown in Fig. 5, and will serve to eliminate trouble and interference due to slight mechanical vibration of the device.

Preferably also there are tubes of non-magnetic material 18 laid intermediate between the consecutive shields of both layers, and a similar non-magnetic tube is also laid between the solenoids and each of the magnetic shields close thereto. This fact is evident from Fig. 5 in particular.

The incoming radio signal currents are carried by conductors passing through the shields and thus subject directly to the influence of said shields. These conductors are so woven back and forth through the shields as to substantially eliminate self-capacity while being fully subjected to the magnetic influence of the north magnetic pole. For this purpose the incoming aerial lead-in connects to the connection 19 which divides into the two wires 20 and 21 in parallel. The wire 20 passes across through the first top shield to the left, then down diagonally and back through the third bottom shield to the right; and up diagonally and across the fifth top shield to the left, then down diagonally

and back through the seventh bottom shield to the right; then up diagonally and across through the ninth top shield to the left; then down diagonally and through the tenth bottom shield to the right; then up diagonally and across through the eighth top shield to the left; then down diagonally and back through the sixth bottom shield to the right; then up diagonally and across through the fourth top shield to the left; then down diagonally and back through the second bottom shield to the right where it comes out adjacent to the point where it first entered.

The other wire is woven back and forth through the unoccupied shields in a manner similar to the above explanation for the wire 20, except that it occupies a lower shield in place of each of the upper shields occupied by the wire 20 and then occupies an upper shield in place of each of the lower shields occupied by the wire 20.

The terminal ends of both of the wires 20 and 21 are joined together as shown at 22, and this terminal is then connected to the aerial connection of the receiving set. It will be noted that the above system of splitting the incoming circuit into two parts makes it possible to so weave the wires back and forth as to secure perfect cooperation and influence from the magnetic shield, while at the same time entirely eliminating any interference due to self capacity.

The other or south magnetic ends of the cores 7, 8, 9 and 10 are connected to a condenser 23 which serves as a storage reservoir for use in connection with particularly heavy drains on the system. This condenser comprises a series of laminations or plates 24 and another series of such plates 25, the plates of the two series criss-crossing each other as best shown in Fig. 1. There is also another series of said plates 26 extending straight across the condenser. Each of the plates 26 is wrapped or protected with a covering of silk or similar high electrostatic material 27, preferably wrapped around such plate as is clearly evident from Fig. 3. Furthermore the ends of the plates 26 are also mounted on the binding posts 28 and 29 upon which they may be tightened up.

Due to the fact that the plates 24 and 25 cross between the plates 26 and the insulating layers 27 it is preferred to place washers or the like 28 on the binding posts intermediate between the ends of the plates 26 so that when the nuts 29 are tightened up on the binding posts the plates 26 will not have their ends seriously distorted.

Plates 25 and 26 are grounded by a ground wire 30 connected together at a convenient point as shown in Fig. 1.

Manifestly the magnetizing current supplied to the solenoids may be controlled in any convenient manner, but for purposes of illustration there is shown in Fig. 1 diagram-

matically a rheostat 31 having a movable contact arm 32 and an end terminal 33 so that by connecting the terminals 15 and 33 to the source of current supply and adjusting the rheostat the amount of magnetization can be adjusted to any desired degree.

If desired there may be inserted a layer of non-magnetic material between the two central laminations of each polar group so as to improve the distribution of the magnetic effect to the shields of the top and bottom layer.

It will generally be found desirable to operate the magnetic system up to a rather high degree of saturation so that the operation is above the "knee" of the magnetization curve.

While there has herein been shown and described only a single embodiment of the features of the present invention still it is not intended to limit the invention thereto except as it may be so limited in the claims.

What is claimed is:

1. In a radio signal receiving system, the combination with a conductor for incoming radio frequency currents, of means for reducing static interference including a magnetic shield embracing said conductor, a solenoid in conjunction with said magnetic shield and serving to magnetize the same to create a north magnetic field in the shield, and means for regulating the strength of a magnetizing current in said solenoid, substantially as described.

2. In a radio signal receiving system, the combination with a conductor for incoming radio frequency currents, of means for reducing static interference including a magnetic shield in proximity to said conductor and constituting the north magnetic pole of a magnetic system, substantially as described.

3. In a radio signal receiving system, the combination with a conductor for incoming radio frequency currents, of means for reducing static interference including means under the control of the operator for creating a magnetic field in proximity to said conductor and of desired strength and polarity, substantially as described.

4. In a radio signal receiving system, the combination with a conductor for incoming radio frequency currents, of means for reducing static interference including a bar magnet having one pole in close proximity to said conductor and directly influencing the same, a condenser in conjunction with the other pole of said magnet and directly influencing the same, and means for controlling the strength of magnetism in said magnet, substantially as described.

5. In a radio signal receiving system, the combination with a conductor for incoming radio frequency currents, of means for reducing static interference including a bar magnet having one pole in close proximity to said conductor and directly influencing the same, and a condenser in conjunction

with the other pole of said magnet and directly influencing the same, substantially as described.

6. In a device of the class described, the combination of a conductor for radio frequency currents comprising a pair of wires in electrically parallel relationship, a series of tubular shields of magnetic material surrounding said wires, a series of bar magnets having their cores formed of laminations, the end portions of the laminations being in contact with the individual shields, and means for individually magnetizing the bar magnets aforesaid, substantially as described.

7. In a device of the class described, the combination of a conductor for radio frequency currents comprising a pair of wires in electrically parallel relationship, individual tubular shields of magnetic material surrounding said wires, the wires and shields being interlooped to establish a neutralized self-capacity condition, and means for creating a magnetic field with all of said shields located in the north magnetic pole thereof, substantially as described.
